UNITED STATES PATENT OFFICE

166,453

MEDALLION

John D. Cuccio, South Bend, Ind., assignor to The
Studebaker Corporation, South Bend, Ind., a
corporation of Delaware

Application January 2, 1951, Serial No. 13,652

Term of patent 3½ years

(Cl. D14—6)

To all whom it may concern:

Be it known that I, John D. Cuccio, a citizen of the United States, residing at South Bend, in the county of Saint Joseph and State of Indiana, have invented a new, original, and ornamental Design for a Medallion, of which the following is a specification, reference being had to the accompanying drawings, forming a part thereof.

In the drawing:

Figure 1 is a front elevational view of a medallion showing my new design;

Figure 2 is an end view of the medallion;

Figure 3 is a plan elevation of the medallion; and

Figure 4 is a vertical sectional view taken on line 4—4 of Figure 1.

I claim:

The ornamental design for a medallion, as shown.

JOHN D. CUCCIO.
